PAPER CRIMPING DEVICE

William N. Thode, Chicago, Ill., assignor to
Seiders-Mather Corporation, Chicago, Ill., a
corporation of Delaware

Application December 31, 1931, Serial No. 584,163

2 Claims. (Cl. 93—1)

This invention relates to improvements in paper crimping device, and more particularly to machines for fastening sheets of paper together by passing them between inter-meshing crimping wheels which act to impress a narrow line of crimping along one or more edges, thereby accomplishing in a more or less permanent manner what is usually accomplished by the use of metal fasteners, rivets, and the like, the fastening being what may be termed semi-permanent in that the sheets can be parted with but slight mutilation.

The object of the invention is to provide an improved crimping device, sturdy and simple in its construction and suitable for general use in offices for the uniting of sheets of written matter and correspondence together for filing purposes.

A preferred embodiment of my invention is disclosed in the accompanying drawings, in which

Figure 1 is a general view in front elevation of the device attached to the edge of a table or desk;

Figure 2 is a top plan view of the device;

Figure 3 is a view of the device in vertical section as taken on line 3—3 of Figure 2;

Figure 4 is a view in side elevation;

Figure 5 is an illustrated view of several sheets of paper crimped together; and

Figures 6 and 7 are enlarged detail views in elevation and section, respectively, of a fragment of the crimped sheets.

As shown herein, the device is designed for attachment to the edge of a table or desk and to be operated by a crank located outwardly beyond the edge and rotative about a horizontal axis. In common therefore with devices intended for table attachment, the machine has a cast metal frame consisting of a main portion 1 adapted to rest upon the top of the table and form the base for the moving parts, a V-shaped yoke 2 extending downwardly from the outer edge of the main frame portion and thence curving inwardly to extend beneath the top, and finally a clamping screw 3 mounted at the lower end of the yoke.

The main portion of the frame 1 consists generally of a longitudinal web 1^a having transverse webs 1^b, 1^b at each end which form the feet which rest upon the table surface. The frame also supports a horizontal feed plate 4 for the work to be crimped, the same being elongated in the direction of the edge of the table and to which the device is attached with the plate elevated an inch or so above its surface. Just

above and below the plate are two crimping wheels 5 and 6 which mesh with each other through a slot 4^a formed near one of the longitudinal edges of the plate and substantially in the plane of the surface of the plate.

The longitudinal web 1^a of the frame has an upstanding flange 7 against which one of the longitudinal edges of the feed plate abuts, said flange being spaced a short distance outwardly from the plane of the two crimping wheels and along its top edge the flange has a lip projecting toward the plane of the wheels, thereby forming a laterally facing channel 7^a for guiding the edges of the sheets of paper as they are fed along the plate 4 and between the crimping wheels.

Extending outwardly from the frame and in prolongation of the axis of the lower crimping wheel 6 is a cylindric journal bearing 8 for a shaft 9, on the inner end of which is mounted said lower crimping wheel. At the outer end of this shaft is a crank 10 which is turned by hand for driving the lower crimping wheel.

A bearing member 11 integral with the frame 1 supports the upper and driven crimping wheel 5, said wheels having cut in their narrow and somewhat rounded peripheries, small fine teeth 12 which resemble milling rather than gear teeth, although they are accurately cut so that they mesh perfectly with each other even through one or more sheets of paper.

The bearing consists of two bearing members 11^a, 11^b in alignment with each other and having a space between to accommodate the upper wheel 5, this space being bridged by a pair of V-shaped yokes 11^c integral with the spaced bearing members. Extending axially of the bearing is a spindle 13 having a central journal bearing 13^a on which the wheel 5 is journaled and a collar-like flange 13^b formed a short distance inwardly from its end. The outlying bearing member 11^b is bored axially and at its outer end is a seat or socket for the flanged end of the spindle 13, the portion of the bore forwardly of said socket being of somewhat greater diameter than the adjacent portion of the spindle. The inner bearing member 11^a also has an axial bore considerably larger than the spindle and is internally threaded to receive the threaded shank of a tension adjusting screw 14 having a relatively large disc 14^a with a milled edge at its outer end. The shank 14^b of the adjusting screw is tubular with a tapered bore 14^c decreasing in diameter toward the outer end where it assumes the diameter of the outer spindle extension 13^a and forms a pilot bearing therefor.

The adjustment required is that of shifting the upper or driven crimping wheel 5 toward or from the lower and driven crimping wheel 6, in order to vary the pressure exerted by the 5 wheels in crimping sheets of different thickness, or a greater or lesser number of sheets together. The amount of adjustment is comparatively small so that the actual displacement of the spindle is quite limited though positive nevertheless, and 10 is accomplished in the following manner: In forming the bearing socket for the flanged end of the spindle the same is bored slightly off center to the true axis of the bearing so that when the spindle is assembled without the adjusting screw 15 in place, the spindle 13 is inclined slightly upwardly with respect to the true axis, which manifestly would raise the upper crimping wheel 5 with respect to the lower wheel but not enough to throw the teeth out of mesh. But on applying the adjusting screw 14 with its tapered bore, 20 the outer end of the spindle is depressed as it is guided into the pilot bearing at the outer end of the tapered shank, thus depressing the wheel slightly as the spindle is sprung sufficiently to 25 lower the journal bearing 13^a on which the wheel rotates. Thus the farther in the shank of the adjusting wheel is turned the closer together the wheels are brought and the greater the crimping pressure exerted on the sheets of paper.

30 Now to operate the machine, the sheets of paper S to be fastened together are arranged so that the edges to be crimped coincide with each other and then feeding the sheets toward the wheels with one hand, the crank is turned with the other.

35 In this operation the feed plate 4 supports the sheets in flatwise position and the groove or channel 7^a along the edge of the feed plate guides the edges of the sheets in a straight path and at a uniform distance of approximately $\frac{1}{4}$ inch 40 beyond the crimping wheels so that the line of crimping C (Figure 5) extends in a straight line across the margins of the overlapping sheets about the same distance inwardly from their coinciding edges.

45 The crimping is manifestly the result of pressing the fine intermeshing teeth into the fibrous texture of the paper with sufficient force to bring about a close adhesion but without in any way appreciably rupturing the fibers, although the 50 crimping is usually so positive that at least one of the sheets will tear along the line of crimping before they will separate. In other words,

the crimping is not the equivalent of a permanent fastening, as for instance by stapling, but is more in the nature of a semi-permanent fastening in that the sheets can be separated after they are crimped by ripping or pulling them apart, although it is not always possible to do so without some tearing along the line of crimping. As shown in Figure 5, the line of crimping is quite narrow (approximately $\frac{3}{4}$ of an inch) and resembles somewhat a line of stitching but without the use of any agency other than the adhesion between the many minute interlocked fragments of the overlapping sheets.

Having set forth a preferred embodiment of my invention,

I claim:

1. In a crimping device, the combination of a frame, a pair of rotative crimping wheels, a fixed bearing on said frame for one of said wheels, and an adjustable bearing for the other of said wheels comprising a hollow bearing member having sections spaced axially apart to accommodate the last mentioned wheel therebetween, a spindle extending axially of said bearing member and supporting the wheel intermediate its ends, one end 100 of said spindle being seated in a socket in one of the sections of said bearing member and offset slightly from the true axis of the bearing, and an axially adjustable member mounted in the other section of said bearing member and forming a seat for the other end of said spindle and operative to shift the said last mentioned wheel toward and from the first mentioned wheel.

2. In a crimping device, the combination of a frame, a pair of rotative crimping wheels journaled on said frame, one of said wheels being rotative about a fixed axis and an adjustable bearing for the other wheel comprising an elongated hollow bearing member, a spindle extending axially of said bearing member and supporting said wheel intermediate its ends, one end of said spindle fitting into a socket at one end of said bearing member and offset from the true axis of the spindle, and an adjusting screw having a tapered internal bore providing a bearing 120 for the other end of said spindle and having screw threaded engagement with the opposite end of said bearing member and adjustable axially of said spindle to shift the same toward and from said driving wheel.

WILLIAM N. THODE.
